United States Patent Office

Des. 188,855
Patented Sept. 20, 1960

188,855

COMBINED SCORE TABLE AND SCORE PROJECTOR OR THE LIKE

Richard G. Reineman, Covina, Calif., George E. Schaefer,
Muskegon Heights, Mich., and George H. Hart, Chi-
cago, Ill., assignors to Brunswick Corporation, a cor-
poration of Delaware

Filed Apr. 15, 1960, Ser. No. 60,202

Term of patent 14 years

(Cl. D34—5)

Fig. 1 is a perspective view of a combined score table and a score projector or the like showing our new design; Fig. 2 is a rear elevational view thereof; Fig. 3 is a side elevational view thereof; and Fig. 4 is a front elevational view thereof. The dominant features of our new design are shown in full lines on the drawings.

We claim:

The ornamental design for a combined score table and score projector or the like, as shown and described.
